(57) **CLAIM**

The ornamental design for a telephone base station, as shown and described.

DESCRIPTION

FIG. 1 is a front perspective view of a telephone base station in accordance with my new design;

FIG. 2 is a front view thereof;

FIG. 3 is a left-side elevational view thereof;

FIG. 4 is a right side elevational view thereof;

FIG. 5 is a top plan view thereof;

FIG. 6 is a bottom plan view thereof; and,

FIG. 7 is a rear view thereof.

The broken lines in the figures are directed to environment and depict portions of the telephone base station that form no part of the claimed design.
